Primary Examiner—Wallace R. Burke*Assistant Examiner*—Lavone D. Tabor*Attorney, Agent, or Firm*—Marshall, O'Toole, Gerstein,
Murray & Borun[57] **CLAIM**

The ornamental design for a floor scrub brush head, as shown and described.

DESCRIPTION

FIG. 1 is a top, front and right side perspective view of a floor scrub brush head showing my new design;
FIG. 2 is a right side elevational view thereof;
FIG. 3 is a left side elevational view thereof;
FIG. 4 is a front elevational view thereof;
FIG. 5 is a rear elevational view thereof;
FIG. 6 is a top view thereof; and,
FIG. 7 is a bottom view thereof.

The bristles, and handle attachment device in broken lines, shown in the drawings are for illustrative purposes only and form no part of the claimed design.
